UNITED STATES PATENT OFFICE.

HOWARD B. JONES, OF CHICAGO, ILLINOIS.

GAME APPARATUS.

1,242,198.

Specification of Letters Patent.

Patented Oct. 9, 1917.

Application filed November 4, 1916. Serial No. 129,440.

To all whom it may concern:

Be it known that I, HOWARD B. JONES, a citizen of the United States, and a resident of Chicago, in the county of Cook and State 5 of Illinois, have invented certain new and useful Improvements in Game Apparatus, of which the following is a specification.

My invention relates to game apparatus. Its principal objects are to provide interest 10 and amusement.

In the accompanying drawings, which form a part of this specification I have shown a preferred embodiment of the invention, Figure 1 being a top plan or face view 15 of the same; Fig. 2 being a side view of the same, the base portion being shown in section, as on the line 2—2 of Fig. 1; Figs. 3 and 4 are side and top views respectively of one of the counters, on an enlarged scale; 20 and Fig. 5 being a perspective view of a form of track or guide for the playing ball.

The substantially flat base or board 10 is preferably circular and contains a plurality of substantially parallel grooves 11, which 25 are shown as circular and concentric. Between the grooves 11 there occur ridges, as 12, the ridges and grooves preferably rounding into each other. The preferred character of these grooves and ridges and their 30 arrangement with respect to each other is well shown in the drawings. In practice I make the device with seven such grooves and number them consecutively from 1 to 7 inclusive as shown in Fig. 1. I also color the 35 grooves variously, for instance, orange, blue, brown, red, black, yellow and green, thus giving the device an attractive appearance, as well as facilitating the playing of the game and adding to its interest.

40 In one form of play with this device the various grooves are given an arbitrary value. For instance, 10—15—25—50—75—100 and 20, in consecutive order from the outer to the inner groove, these numbers indicating 45 approximately the relative degrees of difficulty in scoring in the respective grooves. The grooves may be given any other arbitrary values. They may also be in other arrangement than circular, although the 50 circular arrangement brings added features of interest and skill into the play over, for instance, an arrangement of the grooves in squares.

For playing the game a playing device, 55 preferably one which rolls, and preferably a ball, as 14, is employed, which ball is

preferably of metal, having in view its advantageous weight for this game. In practice I employ steel balls such as are used for bearings in automobile hubs and 60 the like. As the game is a competitive one, and can be played by a number of persons at the same time I provide at least four balls with each game. These balls are suitably 65 about seven-sixteenths of an inch in diameter where the grooves 11 are on the curve of a circle, approximately three-fourths of an inch in diameter, although I have used somewhat larger balls with good results.

The ball may be projected by the player 70 in any approved way, for instance, merely by hand, its forward roll being started on the outer flat surface 20 of the base. Preferably I employ a light wire double track, as 15, about eight inches in length which 75 may be held by the player at a tilt or angle with respect to the base, as shown at the left hand side of Fig. 2, whereby the ball 14 is projected downward by gravitation upon the board 10 at various rates of travel ac- 80 cording to the tilt of the track 15. This track or ball-projecting device 15 may be rested upon the table supporting the base 10, as shown at the right hand side of Fig. 2, whereby the ball may be projected upon 85 the board by the player's finger and with varying rates of travel according to the strength of the stroke employed.

The object of the player is to cause the ball 14 to come to rest in a particular one 90 of the grooves 11. In order for it to come to rest in any other groove than No. 1 it must travel over one or more of the obstructing ridges 12. Quite a degree of skill 95 is called for to cause the ball to stop at the several desired grooves. With the apparatus thus far described the game may be played by the opposing parties making an effort to place the ball in the grooves of the higher valuations, the player each time calling the groove for which he is playing, with a penalty of a given number of points, say 10, in case of failure.

I prefer, however, to include in this game another feature, and one which is of very 105 decided interest and amusement to the player, namely, that of the pole or post 16 and the markers 17. The post 16 is readily positioned upright upon the base 10 by simply inserting same in the central opening 18, 110 which opening may be provided with a metallic bushing 19. I have shown the post as

provided with a plurality of means for holding a marker at given places thereon, which means may be of any approved form and are preferably recesses or necks 19, the pole 5 thus being given an ornamental appearance, as well as simplifying the construction. In some forms of markers, however, the post need not be specially adapted to accommodate them. The markers 17 are suggestive 10 of the head and body of a person, a miniature effigy, having spring arms 20, consisting of a single piece of wire passing through a hole in the marker and being bent substantially U-shaped as shown. As illustrated in 15 Fig. 2, these markers may be applied to the pole at any of the reduced portions 19. These effigies appear to be climbing the pole, and the object of the player, where these counters are used, is to have his effigy counter 20 climb to the top of the pole before any other player's counter gets there.

The pole itself is preferably colored, for instance in the order of green, blue, brown, yellow, black, orange, red, brown, yellow, black, green and red, from the bottom to the top. The four counters with which the game is provided are also preferably colored, and with different colors, so that they may be readily distinguished. On the base 10 I 25 show a colored marker, for each of four players, for instance, blue, red, yellow and green, as indicated at 21. The counters 17 are given the same colors respectively.

An approved manner of playing the game 30 is as follows:

The players being arranged around the board or base 10, which should be placed upon a substantially solid support, for instance a table, one player begins by projecting 35 one of the balls 14 upon the base 10 and over the ridges 12. If he succeeds in placing his ball in the central groove, No. 7, which is colored green, he places his counter 17 in the lowermost notch or neck 19, or, in other 40 words, in association with the lowermost counting position on the post 16. Having succeeded, he plays again, this time endeavoring to place the ball in groove No. 2, which is colored blue, the next corresponding color 45 on the post being blue. If he again succeeds, inasmuch as the next succeeding color on the post is brown, he tries for groove No. 3, which is colored brown. If he succeeds 50 again he tries for groove No. 6, yellow, the next position in his counter's advance upward on the post being yellow. In this manner he continues to play so long as he is successful; but upon failure to place the ball in the groove which he is then attempting, 55 he ceases playing and the opponent begins. The second player must now first endeavor to place his ball in groove No. 7, and he cannot count until he does so, after which he tries for the blue and then the brown, just as I have mentioned the practice in de-

scribing the assumed course of the first player. Upon failure by any player at any point the next player in order begins.

It will be noted that the post is colored red and green at two places respectively. When any player's count is immediately below one of the green or red sections on the post it is his object to place his ball in the red or green groove as the case may be, in order to accomplish that point and advance in the pole-climbing operation. If, however, the player's ball happens to come to rest in either the red or the green trough or groove at a time when he is trying for some other groove he is penalized by having to move the marker, as 17, downward one color on the post. It is pointed out that the yellow groove, No. 6, is particularly difficult of accomplishment in play, and that the player's ball is exceedingly likely to go beyond it and into the green compartment, No. 7, thus calling for a lowering of the player's counter one point. It is quite frequent during every game that the player's ball stops inopportunistically in the green or red groove, giving rise to much hilarity on the part of the opponent.

Considerable skill may be developed in playing the game, and it is pointed out that some players can best secure results in at least the outermost three grooves by directing the ball at an acute angle to the grooves and ridges instead of directly across them. The possibility of directing the ball at any desired angle to a given groove brings into the game a large degree of interesting variety of operation and expression of skill.

The base, pole, and counters are preferably made of wood and the track 15 and counter arms 20 of wire. The grooves and ridges in the base, as well as the modification of the post, where the device is constructed as illustrated, are formed in a lathe according to practices well understood.

While I have illustrated and described a preferred embodiment of my new game apparatus and have shown approved ways of using the same the invention is not limited to the specific apparatus illustrated and described, and it will be apparent that the game may be played according to other rules. Reference should be had to the appended claims to determine the various changes and modifications which I contemplate as falling within the scope of the present invention.

I claim:

1. Game apparatus comprising a base having on the top surface thereof a plurality of substantially concentric grooves and intervening ridges, a track device adapted to be held in the player's hand and rested upon the marginal portion of the base, a rolling device adapted to be positioned on the track device and thereby projected substantially

toward the center of said concentric grooves, said track being such that by raising or lowering one end thereof said rolling device positioned thereon will be projected over 5 said ridges with varying forces respectively.

2. Game apparatus comprising a substantially flat base having concentric grooves and intervening ridges on the upper surface thereof, a rolling device adapted to be propelled over one or more of said ridges and to come to rest in one of said grooves, a score counting device associated with said base, and means for projecting said rolling device over one or more of said ridges from the 10 15 marginal portion thereof substantially toward the center of said grooves.

3. Game apparatus comprising a substantially flat base having a plurality of substantially parallel ridges in the upper surface thereof, a post extending upward from said base, and markers adapted to engage said post at various elevations thereon, a playing device adapted to pass over one or more of said ridges and to come to rest in one of 20 25 said grooves, said markers being adjustable on said post to indicate the score or count of said playing device in the respective grooves.

4. Game apparatus comprising a substantially flat base having concentric grooves and intervening ridges in the upper surface thereof, a rolling device adapted to be propelled over one or more of said ridges and to come to rest in one of said grooves, a post 30 35 upstanding from said base, a counter readily adjustable to various positions on said post, and corresponding identifying means

associated with said grooves and with said post whereby a count registered by said rolling device in one of said grooves may be 40 indicated by said counter on said post according to said corresponding identifying means.

5. Game apparatus comprising a substantially flat base having concentric grooves 45 and intervening ridges on the top surface thereof, a post upstanding substantially from the center of said base, a plurality of counters adapted to be readily adjustable respectively at various positions on said 50 post, a metallic ball, a track device for projecting said ball in a rolling manner over some of said ridges, said ball being adapted to come to rest in one of said grooves, said post and said grooves having respectively 55 associated therewith corresponding indicating means, said counters being adapted to register the counts made in said respective grooves by said ball.

6. Game apparatus comprising an upright pole, a counter readily adjustable to various positions on said pole, means on said pole for indicating such various positions, and a playing apparatus auxiliary to said pole, said playing apparatus being such 60 65 that a player operating the same can make a count or score thereby, said playing apparatus and said pole having corresponding indicating means whereby a count or score made by a player on said playing apparatus may be registered by said counter on said pole at such corresponding indicating means.

HOWARD B. JONES.
